UNITED STATES PATENT OFFICE.

FRANK D. HOWE, OF AKRON, OHIO, ASSIGNEE, BY MESNE ASSIGNMENTS, TO INTERNATIONAL HARVESTER COMPANY, A CORPORATION OF NEW JERSEY.

COOLING DEVICE.

1,400,878.

Specification of Letters Patent. Patented Dec. 20, 1921.

Application filed August 31, 1916. Serial No. 117,887.

To all whom it may concern:

Be it known that I, FRANK D. HOWE, a citizen of the United States, residing at Akron, in the county of Summit and State of Ohio, have invented certain new and useful Improvements in Cooling Devices, of which the following is a full, clear, and exact specification.

This invention relates to cooling devices. 10 One of the objects of the invention is to improve the efficiency of cooling devices.

Another object is to simplify and improve the general arrangement of cooling devices as used particularly in connection with engines for propelling motor vehicles. 15

Another object is to provide a cooling system for motor vehicle engines and the like adapted to meet all the requirements for successful commercial operation.

20 These and other objects are accomplished by providing the combination of a tank for receiving a fluid to be cooled, cooling tubes extending through the tank, and means in the tank causing the fluid to take a prolonged path in intimate contact with said tubes.

The invention is illustrated on the accompanying sheet of drawings, in which—

Figure 1 is a fragmentary side elevation 30 of a motor vehicle engine, the water jacket of which is connected to my improved cooling device, parts of which are shown in section;

Fig. 2 is a rear elevation of my cooling device; and

Fig. 3 is a top plan view, parts being in section, showing the arrangement of the cooling tubes and the diaphragm for causing the fluid to be cooled to take a prolonged path in contact with the tubes. 40

The various novel features of my invention will be apparent from the following description and drawings and will be particularly pointed out in the appended claims.

I have chosen to illustrate my invention in connection with an internal combustion engine 10 which is used for propelling a motor vehicle, said engine having its cylinders 50 water-cooled, the water jacket 11 having a cold water inlet 12 and a hot water outlet 13. As is well understood, the hot water passing out of the water jacket of an engine is passed through a cooling device where

the heat is removed, the water again, in a 55 cooled state, passing into the lower part of the water jacket, as in the thermo-siphon system. My radiator or cooling device includes an outer casing 14 which is substantially closed, there being, however, a circular 60 opening 15 in the rear wall of the casing, in the neighborhood of which a fan 16 is driven from the engine 10 through a suitable driving connection 17. The upper front portion of the casing is also provided with 65 an opening in which is located a screen 18 which permits the passage of air therethrough for cooling purposes. The radiator also includes upper and lower compartments or water tanks 19 and 20 which are connected 70 by suitable vertically arranged pipes 21. For the most part the tanks 19 and 20 and pipes 21 are spaced from the casing 14 to permit circulation of air therebetween. The engine water jacket 11 and the radiator are 75 filled with water by pouring the same through the upper neck portion 22 of the casing 14 when the cap 23 is removed therefrom, there being a suitable overflow pipe 24, the upper end of which is in the neck portion 22 and the lower end of which overflow pipe extends to a convenient point of exit where water dripping out will not be objectionable.

In water cooling systems for motor vehicles, it is realized by all that unless some special precaution is taken, the engine cooling water will boil away rapidly, causing the many well known troubles which follow. This cooling water, which becomes 90 heated to an extremely high degree in water jackets, has a great tendency to, and in a great many cases does, bubble and spout over into the overflow pipe, causing a considerable loss of the water. At the same 95 time a considerable amount of steam is carried away in excess to the overflow pipe in many cooling systems now employed. It is this undesirable waste of water and steam which, among other things, I have attempted 100 to overcome.

To accomplish this result and to render more efficient the cooling of the fluid for the purpose of maintaining engines in a relatively cool and economical operating condition, I have provided the upper compartment or water tank with a plurality of longitudinally extending tubes 25 through which a

cooling fluid, such as air, may pass. The front end of these tubes register with the screen portion 18 of the outer casing so that air forced through the tubes 25 may take a direct path through the tank. A relatively large number of these air tubes 25 are provided so that the hot water passing into the upper tank 19 will necessarily come into fairly intimate contact with these tubes which have a cooling effect upon the water. It is desirable to improve the efficiency of the radiator or cooling device by causing the hot water to remain in intimate contact with the cooling tubes as long as possible. For this reason I have provided a baffle 26 in the form of a plate or partition which is located in the upper tank 19 and runs transversely to the air tubes 25, the ends of the baffle, however, being spaced from the outer ends of the upper tank 19. This baffle is also located slightly in the rear of the vertical water pipes 21 which connect the upper and lower water tanks 19 and 20. By means of this arrangement it is apparent, reference being had particularly to Figs. 2 and 3, that the hot water, which passes out from the engine water jacket through the pipe 13 and through the connection 27, enters the upper tank 19 of the radiator through the conduit 28 leading into the central rear portion of the tank 19. This hot water immediately is caused to branch in opposite directions by the position of the baffle 26, the water passing transversely with respect to the air tubes 25, by means of which the water is cooled. This water passes outwardly to either side at the rear of the baffle in intimate contact with the air tubes until it reaches the ends of the baffle, whereupon the water then passes inwardly transversely with respect to the air tubes in the front portion of the water tank 19. When this water reaches the central portion of the front part of the radiator, it passes downwardly through the water pipes 21 into the lower tank 20, from which it automatically passes upwardly into the water jacket through the conduit 12. In this manner it is seen that the hot water in the upper tank 19 is forced to take a prolonged path in intimate contact with the air tubes, whereby the water is efficiently cooled. In this manner the water is prevented from bubbling out into the overflow pipe and at the same time most of the steam which accompanies the hot water is condensed so that even under the most severe operating conditions a relatively small amount of steam passes out through the overflow pipe 24.

The cooling air is drawn through the screen 18 through the air tube 25 and out through the rear opening 15 by the fan 16. At the same time air passes downwardly around the water pipes 21 and around the lower water tank 20 and then out through the opening 15, whereby all parts of the

water circulating system are maintained relatively cool in a most efficient manner.

It is evident that there may be various modifications of my invention as herein particularly shown and described, and it is my intention to cover all such modifications which do not involve a departure from the spirit and scope of my invention as set forth in the following claims.

What I claim is:

1. A cooling device for internal combustion engines having upper and lower compartments, a plurality of horizontal cooling tubes in the upper compartment, a vertical baffle plate extending transversely of the cooling tubes and dividing the upper compartment into front and rear chambers communicating at the ends of the baffle, an inlet for the rear chamber and an outlet for the lower compartment adapted for connection to the waterjacket of an engine, and vertically disposed cooling passages connecting the front chamber and lower compartment, whereby hot cooling water or steam from the water jacket will first enter the rear chamber and be directed by said baffle into contact with the horizontal cooling tubes before passing to the front chamber.

2. A cooling device for internal combustion engines having upper and lower compartments, a plurality of horizontal cooling tubes in the upper compartment, a vertical baffle plate extending transversely of the cooling tubes and dividing the upper compartment into front and rear chambers communicating at the ends of the baffle, a filling opening for the front chamber, an inlet for the rear chamber and an outlet for the lower compartment adapted for connection to the water jacket of an engine, and vertically disposed cooling passages connecting the front chamber and lower compartment, whereby hot water from the jacket entering the rear chamber is directed against the cooling tubes and cooled below the point of ebullition before entering the front chamber.

3. A cooling device for internal combustion engines having upper and lower compartments, a plurality of horizontal cooling tubes in the upper compartment, a vertical baffle plate extending transversely of the cooling tubes and dividing the upper compartment into front and rear chambers communicating at the ends of the baffle, an inlet for the rear chamber and an outlet for the lower compartment adapted for connection to the water-jacket of an engine, the front chamber being in open communication with the atmosphere, vertically disposed cooling passages connecting the front chamber and lower compartment, and means for directing a cooling agent through the horizontal tubes whereby hot cooling water or steam from the water-jacket will first enter the

rear chamber and be directed by said baffle into contact with the horizontal cooling tubes before passing to the front chamber.

4. In a cooling device for internal combustion engines, the combination of upper and lower compartments, a baffle or partition dividing the upper compartment into two communicating chambers, cooling passages extending through the chambers,

10 a plurality of passages affording commun-

cation between one of the chambers and the lower compartment, an outlet for the lower compartment, an inlet opening into the other chamber whereby hot fluid flowing therethrough will be directed by said baffle 15 or partition along the cooling passages before entering the adjacent chamber.

In testimony whereof I affix my signature.

FRANK D. HOWE.
